UNITED STATES PATENT OFFICE.

JAMES C. CRITCHETT, OF EL PASO, TEXAS.

PUZZLE.

No. 884,902.

Specification of Letters Patent. Patented April 14, 1908.

Application filed November 19, 1907. Serial No. 402,855.

To all whom it may concern:

Be it known that I, JAMES C. CRITCHETT, a citizen of the United States, residing at El Paso, in the county of El Paso and State of Texas, have invented certain new and useful Improvements in Puzzles; and I do hereby declare the following to be a full, clear, and exact description of the invention, such as will enable others skilled in the art to which it appertains to make and use the same.

My invention relates to puzzles, and the object of my invention is to produce a puzzle which shall be cheap to manufacture, and will be capable of an almost infinite variety of changes, and will therefore make it easy for the manufacturer to put upon the market a puzzle which shall be as hard to solve or as easy to solve as the demands of the trade may dictate.

20 To these ends my invention consists in a box or other container, preferably cubical in form, adapted to hold a series of irregular shaped blocks each of which is composed of a definite number of smaller unit cubes or 25 other shaped blocks, and which are capable of being put together in such a way as to form a solid.

My invention further consists in the novel combination of parts, and details of construction, more fully hereinafter disclosed and particularly pointed out in the claims.

Referring to the accompanying drawings forming a part of this specification in which like numerals indicate like parts in all the 35 views; Figure 1, represents a perspective view of a cube composed of the various individual blocks constituting my puzzle. Fig. 2, a perspective view of a portion of the parts of my puzzle, with the individual blocks 40 separated from each other. Fig. 3, a like view of other parts of my puzzle. Fig. 4, my complete puzzle assembled, and in its container. Fig. 5, an elevational view of certain parts of my puzzle assembled, and Fig. 45 other parts ready to be assembled, and Fig. 6, a plan view of a cube almost completed from the various parts of my puzzle.

Referring to the above drawings, 1, indicates an irregular shaped block in the general 50 form of a pyramid, and provided with the two rectangular oblong parts 101, and 102, which are square in cross section, and disposed at opposite sides of the block, as shown best in Fig. 2. Between these parts 101 and 55 102, are the oblong rectangular parts 103,

104, 105 and 106, which are also oblong and rectangular in cross section, as shown; and each of these latter portions 103 to 106, are successively twice, three times, four times and five times the height of the portions 101 and 102, and are successively shorter in length than its predecessor by one unit than said parts 101 and 102. That is to say, each of the parts 101 to 106, in dimensions, consists of a plurality of unit cubes of the size of the cube 7; and the parts 101 and 102, each consists of six of such cubes, while the parts 103, to 106, are two, three, four and five of such cubes in height, one of such cubes in thickness, and respectively five, four, three and two of such cubes in length. In other words, the part 101, is a duplicate of the part 102, but stands on end, while the part 102, lies on its side. Similarly the parts 103 and 106, are duplicates, but disposed at right angles to each other, and the parts 104 and 105, are likewise duplicates and likewise disposed at right angles to each other. Similarly the irregular pyramidal block 2, is composed of duplicate parts 201 and 202, each having a volume equal to six unit cubes, disposed at right angles to each other; and also composed of the oblong rectangular blocks or parts 203, 204, 205 and 206, disposed between said parts or blocks 201 and 202, and having precisely the same relations and dimensions relatively to each other as the duplicate blocks 103 to 106, above described. In fact, in the illustration of my invention disclosed in Fig. 2, the pyramids 1 and 2, are what might be called reverse duplicates, in that their volumes and the dimensions of their individual parts are the same, while the said parts in pyramid 1, are offset to the left, and those in pyramid 2, are offset to the right. It results from this reversed offsetting of the individual parts in the two pyramids, that the surface 110, of block 101, may be placed flat against the surface 210, of the block 201, so that the surface 111, of the block 106, will lie against the surface 211, of the block 201. Similarly the surface 116, will match with the surface 216, and the surfaces 115, 114 and 113, will match respectively with the surfaces 215, 214 and 213. Finally the surface 112, will match against the surface 212, and the two pyramids 1 and 2, will fit together as indicated in full and dotted lines in Fig. 2, to form a single larger pyramid.

In addition to the pyramids 1 and 2, I provide an irregularly shaped block 3, best shown in Figs. 1 and 2. This block 3, is composed of the part, or block 301, containing six unit cubes, and a duplicate in all respects to the blocks 101 and 201. It likewise contains the oblong rectangular block 302, having dimensions equal to five unit cubes in length, two unit cubes in width and one unit cube in depth. This block 3, is also composed of the blocks 303, 304, 305 and 306, each one unit cube in depth, three unit cubes in width, and respectively 4, 3, 2 and 1 unit cube in length. These blocks 301 to 306, 15 constituting the larger block 3, are offset to the left, as shown in Fig. 2, and the blocks 301 and 302, are also offset with respect to the blocks 303 to 306, to form the stepped surfaces 310 and 313. This offstepping of 20 the said blocks 301 to 306, permits the surface 320, of the block 301, to fit against the surface 120, of the block 101, the surface 322, of the block 302, to fit against the surface 122, of the block 106, and the corresponding surfaces of the blocks 303, 304, 305 25 and 306, to respectively fit against the corresponding surfaces of the blocks 105, 104, 103 and 102. When the block 3, is thus superposed upon the pyramid 1, as shown in 30 dotted lines in Fig. 2, it serves to further increase the pyramid already composed of the irregular pyramids 1 and 2.

Referring now to Fig. 5, the pyramid composed of the irregular pyramids 1 and 2, and 35 the block 3, is shown in elevation, as well as the steps 310 and 313. Also the blocks 201 to 206, of the irregular pyramid 2, are shown in position, and superposed on said pyramid are the small unit blocks 7, 8, 9, 10, 11, 12 40 and 13. The block 7, occupies the top end surface of the part 101, of the irregular pyramid 1, as best shown in Fig. 2, and the block 8, occupies the right hand portion of the upper surface of the block 122, and fits against 45 the surface 211, of the block 201. The remaining blocks 9, 10, 11, 12 and 13 occupy similar positions with respect to the blocks 106, 105, 104, 103, 102 and 206, 205, 204, 203 and 202.

50 The pyramid shown in Fig. 5, composed of the portions 1, 2 and 3, and the unit blocks 7, 8, 9, 10, 11, 12 and 13 as above described, is further increased by adding the irregular shaped block 6. This block 6, is composed of 55 the smaller blocks 601, 602, 603, 604, 605 and 606, each a unit block longer in length than its predecessor, each a unit block in thickness, and each a unit block greater in width than its predecessor, all as more clearly shown in 60 Fig. 2. This block 6, is superposed upon the block 3, as by moving it to the right, as shown in Fig. 5, so that the extreme right hand surface of the smaller block 601, contacts with the left hand surface of the unit block 7. 65 After this is done, the irregular shaped block

4, shown in Fig. 5, is likewise moved to the right, as shown in Fig. 5, so that its extreme right end fits into the cavity formed between the block 6, and the rest of the pyramid formed by the block 3, and the irregular pyramids 1 and 2. The position of this block 4, is best seen in Fig. 1, as well as the position of the block 6. After the blocks 6 and 4, have been disposed of as above stated, the block 5, may be brought into position, by 70 superposing the same upon the block 2, as shown in Fig. 5, so that its extreme upper end fits against the unit block 7, as best shown in Figs. 1, 3 and 6.

As will be seen from Fig. 3, of the drawings 80 the block 5, like the preceding blocks is composed of smaller blocks, each shorter than its predecessor, the top three formed in steps and the bottom three all of the same width as shown. These various smaller blocks are 85 offset, as shown in Fig. 5, and leave irregular surfaces, to fit against the steps of the pyramid 2, heretofore described. In placing the blocks 3, 4, 5 and 6, into position above described, a cube was formed having a hollow 90 space passing down through the center thereof, as best shown in Fig. 6. Into a portion of this space may be fitted the irregular shaped block 14, as best shown in Figs. 1, 4 and 6. Into another portion of this space is 95 placed the block 15, shown in Fig. 1, on top of the block 15, the block 16, on top of the block 16, the block 18, and in the space thus left the block 17 fits, which completes the 100 cube.

The above operation of assembling the blocks is preferably made within a container 20, which may be of the shape shown in Fig. 4; and be provided with a suitable cover, as 21. The various blocks above mentioned, 105 are so irregular in shape that it is an exceedingly difficult matter to put them together, even after one has succeeded in forming the cube a few times. But the problem of forming the cube may be rendered immensely 110 more difficult by cutting the various parts 1, 2 and 3 etc., into other smaller pieces. Since the volume of each part is composed of a certain number of unit cubes 7, the cutting of the various parts into smaller volumes does 115 not in any wise prevent the said parts from again being fitted together, but since each part may be fit to some other part, in so many different positions, such cutting of the principal parts makes an almost infinite variety of possible fittings together to which the individual parts may be subjected. For example, in practice I propose to cut the parts 1, 2 and 6 each, into at least two or three 120 smaller parts so that the individual parts of the same will not be larger than the parts 14 and 15, now shown in Fig. 2. This cutting of the principal parts would destroy the idea of first forming the pyramids, above disclosed, 125 and would render the operation of putting 130

the various parts of the cube together so difficult that it would be next to impossible to solve the puzzle.

A most important feature of my invention resides in the individual regular shaped parts or unit cubes 7, 8, 9, 10, 11, 12 and 13. For it is so easy to put the larger parts together and leave these individual parts out, that one is almost sure to do it if he does not learn the main idea of first forming the pyramids, and then placing these individual unit cubes in position, as shown in Fig. 5.

Of course my invention is not limited to the forming of a cube. For it is evident that the component parts of my puzzle may be chosen from any rectangular oblong solid. But in all cases component parts must be so chosen that they are each composed of lesser blocks, the volumes of which are definite multiples of some unit volume, which unit volume is always present in my puzzle. Therefore, I do not wish to be understood as limiting myself to the exact details of structure, nor to the arrangement of parts as above disclosed, since it is evident that both may be widely varied without departing from the spirit of my invention.

What I claim and desire to secure by Letters Patent is:—

30 1. In a puzzle, the combination with a series of irregular shaped parts and a series of six cubes, adapted to constitute a larger cube having a volume equal to the combined volumes of the individual parts, substantially as described.

2. In a puzzle, the combination with a series of irregular shaped parts, each composed of a number of unit volumes, and a series of six cubical parts, adapted to form a single cube having a volume equal to the combined volumes of the individual parts, substantially as described.

3. In a puzzle, the combination with a series of irregular shaped parts, each composed of a number of rectangular solid portions and each of said portions having a volume made up of a number of unit volumes, and a series of six regular cubes, each of a unit volume, adapted to form a symmetrical solid having a volume equal to the combined volumes of the individual parts, substantially as described.

4. In a puzzle, the combination with a series of irregular shaped pyramidal parts, and a series of six cubes adapted to fit between said pyramidal parts, to form a single cube having a volume equal to the combined volume of all of said parts, substantially as described.

5. In a puzzle, the combination with a series of irregular shaped pyramidal parts, and a series of irregular and differently shaped other parts, each of said parts composed of smaller parts, and each of said smaller parts having a volume equal to a number of unit cubes, and a series of six unit cubes, the whole adapted to form a single larger cube, substantially as described.

6. A cube for use as a puzzle, consisting of a plurality of irregular pyramidal shaped parts, each consisting of a series of smaller oblong rectangular portions, a plurality of other and differently shaped irregular parts, and a series of unit cubes, said pyramidal and irregular parts and said cubes adapted to fit together to form a single larger cube, substantially as described.

In testimony whereof, I affix my signature, in presence of two witnesses.

JAMES C. CRITCHETT.
